ABSTRACT

Articles are anchored to the interior of the housing of a protective package by two pluralities of protuberances disposed on the housing shells. The two protuberances fall into meshing registry when the shells are brought together. A ramp is disposed on one of the shells to receive the article and position it over the protuberances.

FIG.

2

FIG. 3

PROTECTIVE PACKAGES

DETAILED DESCRIPTION

There is described in copending U.S. application Ser. No. 402,006 a package for the complete and protective enclosure of an article. The package includes a housing having a continuous surface of rigid or semi-rigid material which is banded by a section of sufficiently reduced wall thickness to permit frangible separation into two segments. One of the segments engages the article for removal from the other segment. The article which is packaged can be present in partially assembled form and converted to a fully assembled form upon, and in the course of, removal from the package. One such embodiment is a disposable thermometer which is packaged with a peelably removable shield intervening two strips which carry the operative temperature indicating elements of the thermometer. The shield carries a tab which is anchored to the interior of the package so that removal of the thermometer from one segment of the housing effects peelable removal of the anchored shield from the thermometer.

The present invention pertains to improvements in the means by which such article tabs are anchored. While primarily intended for use in a package such as is described in Ser. No. 402,006, filed on Oct. 1, 1973 the present improvement can be used wherever it is necessary to anchor a tab or strip element to the interior of a rigid or semi-rigid housing.

One anchoring device disclosed in Ser. No. 402,006 involves one or more posts which are defined on the inside surface of one or both of the shells forming the housing. Upon joining the two shells, these posts pass through holes in the article tab thereby engaging it. One disadvantage of such an arrangement is that the entire force applied against the tab upon removal of the article from the housing is localized at the post and thus solely in the region of the hole, thereby increasing the danger of tearing the tab. Moreover, exact alignment of the tab in all three axis is necessary during manufacture in order to properly insert the post through the tab hole. In addition the punching of the holes must satisfy extremely rigid specifications in order to insure proper alignment of the article in the package.

The present invention overcomes these difficulties and facilitates the high speed, automated assembly of the final product. The nature of the present invention will be apparent from the following description and the drawings in which

FIG. 1 is side elevation of a package with a portion broken away to show the tab receiving and anchoring mechanisms of the present invention;

FIG. 2 is a perspective view of a portion of one of the shells forming the housing and

FIG. 3 is a perspective view of a portion of the other shell forming the housing.

Referring now in greater detail to the drawing, housing 11A which is comprised of two segments, 37 and 39 is designed to fully enclose the elements of a disposable thermometer including shield 53 intervening a carrier strip 54 and indicator strip 55. Shield 53 is peelably removed from strips 54 and 55 and these are then brought together to form the indicating portion of the thermometer. For greater detail on the construction and operation of the thermometer, reference may be made to U.S. Pat. No. 3,712,141.

The thermometer components are packed in housing 11A which is divided into two segments 37 and 39 by band 38 which is defined in side walls 29, 30 and 34 by a section of reduced wall thickness, thus permitting the frangible separation of housing 11A into the two distinct segments 37 and 39. The thermometer is engaged by segment 39 by any one of a variety of means described more fully in Ser. No. 402,006 and accordingly separation of segments 37 and 39 results in the withdrawal of strips 54 and 55 from segment 37. By anchoring shield 53 to the interior of housing 11A within segment 37, separation of the two segments also results in peelable removal of shield 53 from strips 54 and 55. For greater details on these operations, reference may be made to the disclosure of Ser. No. 402,006.

In one method of manufacture, the thermometer elements are first assembled and then inserted into one of the shells. The other shell is then brought into registry with the first shell and sealed connection 28 is then made, as by heat sealing. In this operation shield tab 71 must be anchored and there are accordingly provided a plurality of parallel raised protuberances 72 and 73 which are disposed on the inside surface of shell 27 and a second plurality of parallel raised protuberances 74 and 75 on second shell 26. These two sets of protuberances are disposed so that they are brought into meshing registry when shells 26 and 27 are brought into registered connection for sealing. The clearance between the meshed protuberances is sufficient to engage and anchor shield tab 71 and this engagement and anchoring is improved by the serpentine configuration which shield tab 71 assumes when the protuberances mesh. Consequently upon bringing shells 26 and 27 into registry and completing the sealed connection, shield tab 71 is permanently anchored to the interior of segment 37 of housing 11A.

To assist in the registration operation, one shell can be provided with a tongue 76 which slips into a matched opening 77 on the other shell.

The elements of the thermometer are received by one of the shells during assembly along an axis substantially parallel to the longitudinal axis of the housing. In one embodiment the "top" shell 27 is inverted and the thermometer elements are placed upon it, approaching generally as shown by the arrow in FIG. 3. It is important that shield tab 71 be finally disposed over all the protuberances of shell 27 in order to insure proper anchoring when shell 26 is positioned. Tab 71 however is flexible and is often angularly disposed downward from the normal axis of the thermometer elements. In addition, tab 71 may be skewed or twisted. Consequently, there is a tendency for the end of shield tab 71 to catch or snag on the front surface of protuberances 72 or 73 and be prevented from achieving its proper positioning over both protuberances. To prevent this problem, there is provided on one of the shells a ramp 78. Ramp 78 is V-shaped and is disposed on the inside surface of shell 27 about protuberances 72 and 73. Apex 79 of ramp 78 lies in the direction from which shield tab 71 is received. The V-shape of ramp 78 serves to correct any twisting of tab 71 while the incline serves to lift the end of tab 71 over all the protuberances. Towards this end, the ramp rises along an axis perpendicular to the protuberance and longitudinally with the housing from a level substantially flush with the inside surface of shell 27 at apex 79 to a level at the intersection with each protuberance, as at 80 and 81, at least as high as the

protuberance. After intersecting with the protuberance, the incline of the ramp can flatten out.

As a result of the cooperation of the ramp and the protuberances, tab 71 of the article is correctly positioned over the protuberances without the need for 5 punching holes or the like and automatically anchored when shells 26 and 27 are brought together in sealed connection.

The foregoing description and drawings represent a typical embodiment of the present invention but are 10 not intended as limitations on the scope thereof, it being apparent that the invention can be practiced through obvious modifications and rearrangements without departing from the essential spirit thereof.

What is claimed is:

1. In a housing for an article in which the housing includes two shells of rigid or semi-rigid material having complementary surfaces which are joined together in sealed registered connection and the article includes a tab which is received by and anchored to the inside of 20 the housing, an improved article tab receiving and anchoring mechanism comprising

a plurality of parallel, raised protuberances disposed on the inside surface of a first one of the shells at the point at which the article tab is to be anchored, a V-shaped ramp disposed on the inside surface of the same shell about the protuberances, the apex of the ramp's V-shape being disposed in the direction from which the article tab is received and the incline of the ramp rising along an axis perpendicular to said parallel protuberances from a level which is substantially flush with the inside surface of the shell at the ramp's apex to a level at each protuberance at least as great as the height of that protuberance, and

a second plurality of parallel raised protuberances on the inside surface of the second of the shells, the second plurality of protuberances being disposed for meshing registry between the first plurality of protuberances within the V-shaped ramp of the first shell so as to anchor an article tab received by said ramp when said shells are brought into registered connection for sealing.
